(57) **CLAIM**

The ornamental design for an inflatable mattress with bumper, as shown and described.

DESCRIPTION

FIG. 1 is a front perspective view of an inflatable mattress with bumper according to the present invention.

FIG. 2 is a front view of the inflatable mattress with bumper illustrated in FIG. 1.

FIG. 3 is a rear view of the inflatable mattress with bumper illustrated in FIG. 1.

FIG. 4 is a right-side view of the inflatable mattress with bumper illustrated in FIG. 1.

FIG. 5 is a left-side view of the inflatable mattress with bumper illustrated in FIG. 1.

FIG. 6 is a top view of the inflatable mattress with bumper illustrated in FIG. 1; and,

FIG. 7 is a bottom view of the inflatable mattress with bumper illustrated in FIG. 1.

The broken lines depict environment elements of inflatable mattress with bumper that form no part of the claimed design.

1 Claim, 5 Drawing Sheets
